UNITED STATES PATENT OFFICE.

JOHN T. CLARK, OF NEW YORK, N. Y.

LOADING AND UNLOADING DEVICE.

1,109,965.

Specification of Letters Patent.

Patented Sept. 8, 1914.

Application filed October 21, 1911. Serial No. 655,883.

To all whom it may concern:

Be it known that I, JOHN T. CLARK, a citizen of the United States, residing in the city of New York, borough of Manhattan, county and State of New York, have invented a certain new and useful Loading and Unloading Device, of which the following is a specification.

This invention is a means for handling 10 loose material in bags or sacks, such as cement, grain, etc., and is adapted for use particularly in transferring such bags from a certain height to a point below.

It has been attempted heretofore to use 15 ordinary skids and chutes in the form of a slide for handling bags of the character under consideration, but experience shows that such bags cannot be expeditiously handled with such apparatus for the reason that the 20 bags frequently slide off the skid and become lodged and torn in the chute.

This invention obviates the disadvantages 25 of the sliding devices heretofore used, and, for the purposes under consideration, possesses pronounced advantages.

With the objects specified in view, the invention consists of a substantially flat base member on which is mounted, lengthwise of the base member, one or more raised 30 guiding and retaining members, preferably one in the center of said base member. In the present, and what I now consider the best embodiment of the invention, the guiding and retaining member is of a substantially 35 semicylindrical form in cross section.

In a device constructed as specified, the bag of material to be handled, for example cement, straddles the guiding and retaining member, the bag becoming indented 40 so as to embrace or hug the guiding and retaining member, and slide down thereon with a minimum of friction and yet without being displaced or lodged in transit.

In the accompanying drawings, I have 45 illustrated one practical embodiment of the invention, but the construction shown therein is to be understood as illustrative, only, and not as defining the limits of the invention.

50 Figure 1 is a perspective view showing the bag handling device in operative position to a hatchway of a vessel, and Fig. 2 is an elevation of one end of the device showing the bag in position thereon.

55 The device embodies in construction a base member A, and a guiding and retain-

ing member B, mounted thereon and centrally thereof, lengthwise of the base member, said guiding member being shown as semi-cylindrical in cross section. 60

A bag of material C is shown on the device in position for sliding thereon. It will be noted that the weight of the material in the bag causes the bag to sag at either end and to become indented at the center 65 thereof, as shown at d, the center of the bag conforming substantially to the contour of the guiding member B upon which the bag is straddled.

It will be obvious that the device may be 70 used in various ways, but for purposes of illustration I have shown it positioned in the hatchway e in the decks E, E' of a vessel. The device is placed in an inclined position, extending from an upper deck to 75 a lower one, and it will be apparent that the material may readily slide down the device, in the manner described, from one deck to the other.

In practice, for convenience, I usually 80 build a wall composed of a number of bags of material C at the foot of the slideway, and upon which the lower end of the slideway rests, so as to form a stop for the bags when they reach the lower end of the slide- 85 way. The bags are simply dropped onto the slideway, and without particular regard to their being accurately positioned thereon, whereupon they assume the conformation described and slide by gravity to the bottom 90 of the slideway. I have found in practice that the guiding and retaining member soon becomes so smoothed by the bags passing over it that the bags slide down thereon very quickly and with little or no friction, there- 95 by enabling the slideway to be used at a comparatively small incline, and, also, avoid tearing and wear on the bags. In using the device as described, I am enabled to handle bags of material of the character specified 100

much more expeditiously and economically than is possible with chutes or skids heretofore used. Should a slideway of particular length not be sufficiently long to connect the two points between which the material 105 is to be transferred, two or more slideways may be placed in alinement by building up a support at the connecting ends. It will be particularly noted that the slideway is very simple in construction and can be built 110 very economically.

Having thus fully described the invention,

what I claim as new, and desire to secure by Letters Patent is:—

1. An inclined slideway for handling bags of loose material, embodying an imperforate base member, and a guiding and retaining member positioned lengthwise of said base member and substantially intermediate the side edges of said member, the upper surface of the base member being substantially continuous at the respective sides of the guiding and retaining member so as to be exposed for frictional contact with the bag of material, whereby a bag of material deposited upon the slideway becomes indented by contact with the guiding and retaining member so that said bag of material will closely hug said member when sliding down the slideway, the weight of said bag of material being imposed upon the exposed surfaces of the base member and the guiding and retaining member.
2. An inclined slideway for handling bags of loose material, embodying an imperforate base member, the respective side edges of which are free from flanges and the upper surface of which is exposed for frictional engagement with the bags of material, and a guiding and retaining member positioned lengthwise of said base member and substantially intermediate the side edges thereof, said guiding and retaining member being substantially semi-cylindrical in shape and extending upwardly from the base member, whereby a bag containing loose material and deposited upon the slideway becomes indented by contact with the guiding and retaining member.

ing member so that said bag of material will hug closely to said member when sliding down the slideway, the weight of said bag of material being imposed upon the exposed surfaces of the base member and the guiding and retaining member.

3. An inclined slideway for handling bags of loose material, embodying an imperforate base member, the respective side edges of which are free from flanges and the upper surface of which is exposed for frictional engagement with the bags of material, and a guiding and retaining member positioned lengthwise of said base member and substantially intermediate the side edges thereof, said guiding and retaining member being substantially semi-cylindrical in shape and extending upwardly from the base member, whereby a bag containing loose material and deposited upon the slideway becomes indented by contact with the guiding and retaining member so that said bag of material will hug closely to said member when sliding down the slideway, the weight of said bag of material being imposed upon the exposed surfaces of the base member and the guiding and retaining member.

In testimony whereof I have signed my name to this specification in the presence of two subscribing witnesses.

JOHN T. CLARK.
